ROTARY VALVE FOR INTERNAL-COMBUSTION ENGINES.

1,148,283.

Specification of Letters Patent. Patented July 27, 1915.

Application filed September 4, 1914. Serial No. 660,123.

To all whom it may concern:

Be it known that I, SAMUEL G. CROSSLEY, a citizen of the United States, residing in the city and county of Philadelphia, State of Pennsylvania, have invented a new and useful Rotary Valve for Internal-Combustion Engines, of which the following is a specification.

My invention consists of a rotating valve mechanism for a multiple cylinder internal combustion engine, in which the motive fluid (hydrocarbon and air mixed in a gas) is fed into one valve common to the several cylinders and successively fed to the latter.

It further consists of such valve-mechanism in which the valve-casing has a cooling-jacket surrounding the same.

It further consists of such valve-mechanism in which the inlet of motive fluid and exhaust of spent gases into and from a multiplicity of cylinders will occur at stated and invariable relative periods of the revolution of the engine.

It further consists of other novel features of construction, all as will be hereinafter fully set forth.

The annexed drawings and the following description set forth in detail one mechanical form embodying the invention, such detail construction being but one of various mechanical forms in which the principle of the invention may be used.

In said drawings—Figure 1 represents a side elevation of the upper parts of the cylinders of a multi-cylinder internal combustion engine provided with my improved rotary valve. Fig. 2 represents a plan view of one of the heads of the cylinders, seen from below. Fig. 3 represents a vertical section of the valve-mechanism and a part of the cylinder, taken through the inlet-port of the cylinder. Fig. 4 represents a vertical section of the valve-mechanism and a part of the cylinder, taken through the exhaust port. Fig. 5 represents a perspective view of the valve.

Similar numerals of reference indicate corresponding parts in the figures.

Referring to the drawings, the reference numeral 1 indicates a cylindrical valve-casing which is transversely secured across the ends of the cylinders, 2, of which three are herein illustrated.

A cylindrical valve, 3, having an axial bore, 4, closed at both ends, is journaled

with axial pinions, 5, in bearings in the closed ends of the valve-chamber, and are connected by suitable gearing, 6, to a rotary element of the engine to be rotated from the same in unison with the crank-shaft. Pistons, 7, are reciprocable in the cylinders. The valve-casing forms the heads for the upper ends of the cylinders, having rabbed circular seats, 8, fitting upon the open upper ends of the cylinders and secured by bolts, 9.

The walls of the casing are hollow to form a water-jacket, 10, extending the full length of the casing and surrounding the cylindrical valve-seat, 11, extending through the casing and in which the cylindrical valve is fitted to rotate. The portions of the valve-casing which close the ends of the cylinders form each a head for one of the latter, and each of such heads has an inlet-port 12, into and through the valve-seat and an exhaust-port, 13, also into and through such seat.

The inlet-port is parallel with the axis of the valve and is comparatively long in such relation and narrow in relation to the periphery of the valve and seat, and the exhaust-port extends transversely to the axis and is comparatively long in such direction and narrow in its relation to the axis of the valve and seat. The valve casing has a fuel inlet, 14, passing through the valve-casing, water-space and the cylindrical valve-seat, and is suitably connected to a carburetor or similar fuel supply, not shown, and the valve has an annular port, 15, registering with such fuel-inlet and communicating with the axial chamber in the valve to have continual admission of fuel into the axial bore of the valve. Exhaust-passages, 16, extend from the valve-chamber, water-space and casing, one registering with each exhaust port communicating with each cylinder, and directly or indirectly opens to the surrounding atmosphere.

An inlet-port, 17, corresponding to the inlet-port of each cylinder-head in the valve-chamber and adapted to register with such port, passes through the wall of the valve, and said ports are arranged circumferentially in the valve at equal radial distances from each other, in the present instance at three points, so that such ports will successively register with the ports in the valve-chamber as the valve is rotated.

An exhaust recess, 18, is formed in the periphery of the valve at each cylinder-head

to register with each exhaust-port of a cylinder, and each exhaust-port is so arranged in its relative position to the inlet-port of the same cylinder, that the exhaust-port in the 5 valve will register with the exhaust-port in the cylinder-head and again be closed immediately before the coöperating inlet-ports of the same cylinder are brought in register. The exhaust-recesses of the valve extend for 10 about one-third of the periphery of the valve so that ample exhaust is provided.

In practice, the fuel inlet is opened to the supply which is a carburetor of any suitable construction, not illustrated, or other gas 15 supply, and the fuel flows into the valve and, when the engine is started, flows through one of the inlet ports into one cylinder in which the fuel is compressed and ignited and the piston in said cylinder is forced 20 downward. When the piston again ascends, the exhaust-ports are open and the spent gases are exhausted, until the piston arrives at the upper end of its stroke when the inlets are again brought in communication 25 and fuel drawn into the cylinder and again compressed when the piston again ascends and is ignited when the piston arrives at the upper end of its stroke. This operation 30 is performed successively in the several cylinders, so that three explosions successively take place in the engine for each revolution of the engine shaft.

The fuel is continually flowing into the 35 rotating valve and thus continually ready to successively enter the cylinders, and the fuel will be heated by continually entering the valve. The exterior of the valve will be constantly cooled in its seat by the water-jacket surrounding it. The axially long and

peripherally narrow inlet ports admit of 40 fuel being quickly and in large quantities fed into the cylinders, and the narrow and peripherally long exhaust ports and recesses admit of thorough exhaust of the spent 45 gases. The rotating valve will be noiseless 50 and will not be liable to be obstructed or have impurities collect to cause leaks, as is liable to happen with the usual pop-valves, as the valve is continually in motion so long as the engine is in motion.

Having thus described my invention, what I claim as new and desire to secure by Letters Patent, is:—

In an internal combustion engine, a plurality of cylinders, pistons reciprocable in the same, a tubular cylindrical valve chamber connected transversely to one end of each of said cylinders and formed with a main supply port for the explosive fluid and having an inlet port and an exhaust port for each cylinder, and exhaust openings each of which is peripherally alined with an exhaust port, a tubular valve having an axial unrestricted bore, rotatable in said cylinder and formed with an inlet port through its 60 wall for each cylinder to register with the inlet port thereof and with an exhaust recess cut in the wall for each cylinder to register with the exhaust port thereof and formed with a peripheral port through its 65 wall permanently open to the bore of the valve and permanently registering with the explosive fluid port in the valve chamber.

SAMUEL G. CROSSLEY.
